US0D1009824S

(12) **United States Design Patent** (10) Patent No.: **US D1,009,824 S**
(45) Date of Patent: ** Jan. 2, 2024

(54) **WORKSTATION DEVICE**

(71) Applicant: **Cisco Technology, Inc.**, San Jose, CA (US)

(72) Inventors: **Naoki Shimada**, Sunnyvale, CA (US); **Otto Williams**, Berkeley, CA (US); **Shane Michael Costa Martins**, Moraga, CA (US)

(73) Assignee: **CISCO TECHNOLOGY, INC.**, San Jose, CA (US)

(**) Term: **15 Years**

(21) Appl. No.: **29/852,056**

(22) Filed: **Sep. 2, 2022**

Related U.S. Application Data

(63) Continuation of application No. 29/761,150, filed on Dec. 7, 2020, now Pat. No. Des. 962,889.

(57) **CLAIM**

The ornamental design for a workstation device, as shown and described.

DESCRIPTION

FIG. 1 is a top, front, right-side perspective view of a workstation device;

FIG. 2 is a bottom, back, right-side perspective view thereof;

FIG. 3 is a top, back, right-side perspective view thereof;

FIG. 4 is a front view thereof;

FIG. 5 is a back view thereof;

FIG. 6 is a left-side view thereof;

FIG. 7 is a right-side view thereof;

FIG. 8 is a top view thereof;

FIG. 9 is a bottom view thereof;

FIG. 10 is a top, back, right-side perspective view including a disclaimed additional feature of the workstation device (e.g., a modular headphone stand); and,

FIG. 11 is a back view thereof.

The dashed broken lines depict portions of the workstation device that form no part of the claimed design.

1 Claim, 11 Drawing Sheets
